G. C. GEROW

OIL BURNER

Filed Jan. 16, 1925

INVENTOR
George C. Gerow
BY
Chas. W. Rudes
ATTORNEY

UNITED STATES PATENT OFFICE.

GEORGE CARLETON GEROW, OF OTTAWA, ONTARIO, CANADA, ASSIGNOR OF EIGHT-TWENTIETHS TO WILLIAM JOSEPH PRESS, ONE-TWENTIETH TO WILLIAM C. ARNOLD, ONE-TWENTIETH TO JAMES LEWIS KEMP, AND TWO-TWENTIETHS TO EDITH PRESS, ALL OF OTTAWA, CANADA.

OIL BURNER.

Application filed January 16, 1925. Serial No. 2,808.

To all whom it may concern:

Be it known that I, GEORGE CARLETON GEROW, a British subject, residing at the city of Ottawa, in the county of Carleton and Province of Ontario, Dominion of Canada, have invented certain new and useful Improvements in Oil Burners; and I hereby declare that the following is a full, clear, and exact description of the same.

10 My invention relates to an oil burner so constructed that the heat radiated from the combustion bowl is utilized to bring the carburetted air before combustion to substantially the same temperature as that in the combustion zone, thereby obtaining optimum efficiency as regards the complete combustion of the fuel and the thermal units given off.

To this end I have provided the bowl with 20 an enclosing jacket which forms with the bowl an annular chamber; this chamber having air and oil inlets, juxtaposed but separated by a baffle or partition that extends from the jacket to the bowl so that 25 the air entering the chamber is compelled to circulate from the air inlet completely around the bowl to that part of the annular chamber in the vicinity of the oil inlet, where it is carburetted by the oil entering 30 and passing through the annular chamber from the oil inlet to the combustion zone.

For the admission of the oil and carburetted air to the combustion zone, the bowl is provided with an inlet, in line with 35 the oil inlet of the annular chamber, so that the oil thus will pass in a straight line across the annular chamber and create a suction through the annular chamber that maintains forced or rapid circulation of air 40 into and through the annular chamber and around the bowl to the locus or that part of the annular chamber in the vicinity of the oil inlet.

For an understanding of the invention 45 reference is to be had to the following description and to the accompanying drawings, in which:

Fig. 1 is an elevational view of a burner constructed according to my invention,

50 Fig. 2 is a top plan view of the burner shown in Fig. 1,

Fig. 3 is an elevational view at right an-

gles to Fig. 1, showing the air and oil inlets,

Fig. 4 is a horizontal section on the line 55 4—4 Fig. 1, and

Fig. 5 is a vertical section on the line 5—5 Fig. 2.

Like characters of reference refer to like parts throughout the specification and drawings.

The burner comprises a combustion bowl *a*, a jacket *b* surrounding the combustion bowl and forming with it an annular chamber *b'*, and a baffle *e* that extends from the combustion bowl *a* to the jacket *b*. The annular chamber at one side of the baffle *e* is provided with an air inlet *c* and at the other side of the baffle is provided with an oil inlet *d*.

Formed through the wall of the combustion bowl is an inlet *f* from the annular chamber *b'* to the combustion zone or interior of the combustion bowl *a*, and this inlet *f* is in line with the oil inlet *d* so that the oil entering through the oil inlet *d* will pass uninterruptedly across the annular chamber *b'* and through the inlet *f* into the interior of the bowl *a* under the pressure of the oil feed. As the oil passes across that part of the annular chamber between the oil inlet *d* and the inlet *f* to the combustion chamber, it carburets and sucks the heated air into the combustion zone of the bowl and this suction maintains a forced circulation of air from the air inlet through the annular chamber *b'* around the combustion bowl to the inlet *f*. The air during this circulation is heated by radiation from the wall of the combustion bowl and when it reaches that part of the annular chamber *b'* in the vicinity of the inlets *d* and *f* its temperature is raised to a degree corresponding to that of the external surface of the combustion bowl.

The oil entering the interior of the heated combustion bowl *a* is vaporized or gasified and the heated carburetted air combining with the gasified oil forms a mixture that burns with substantially perfect combustion.

Having thus fully described my invention, what I claim as new and desire to secure by Letters Patent is:

1. An oil burner comprising a combustion

- bowl, a jacket surrounding the bowl and forming therewith an enclosed annular chamber, a baffle extending from the combustion bowl to the jacket, an oil inlet
5 through the jacket at one side of the partition and in juxtaposition thereto, an inlet through the wall of the combustion bowl in line with the oil inlet and an air inlet through the wall of the jacket at the other
10 side of said partition and in juxtaposition thereto, whereby the air entering through the air inlet is compelled to circulate around the bowl to a locus between the oil inlet into the annular chamber and the inlet from
15 the annular chamber into the interior of the combustion bowl and is carburetted before passing from the annular chamber into the interior of the combustion bowl.

2. An oil burner comprising a combustion

bowl, a jacket surrounding the bowl and 20 forming therewith an enclosed annular chamber, a baffle extending from the combustion bowl to the jacket, an air inlet into the chamber at one side of the partition and in juxtaposition thereto, an inlet from the 25 chamber into the combustion bowl at the other side of the partition and in juxtaposition thereto, and an oil inlet into the annular chamber in line with the inlet through the wall of the combustion bowl for the admission of the fuel and for creating a suction which draws the air from the air inlet around the annular chamber to the inlet into the combustion bowl.

Dated at the said city of Ottawa, this 26th 35 day of December, A. D. 1924.

GEORGE CARLETON GEROW.
